C. DRESSLER

TUNNEL KILN WITH STEAM GENERATING COOLING ZONE

Filed Nov. 14, 1919

Patented Aug. 5, 1924.

1,503,750

UNITED STATES PATENT OFFICE.

CONRAD DRESSLER, OF NEW YORK, N. Y., ASSIGNOR TO AMERICAN DRESSLER TUNNEL KILNS, INC., OF NEW YORK, N. Y., A CORPORATION OF NEW YORK.

TUNNEL KILN WITH STEAM-GENERATING COOLING ZONE.

Application filed November 14, 1919. Serial No. 338,009.

To all whom it may concern:

Be it known that I, CONRAD DRESSLER, a subject of the King of Great Britain, resident of New York, in the county of New York and State of New York, have invented certain new and useful Improvements in Tunnel Kilns with Steam-Generating Cooling Zones, of which the following is a specification.

10 My present invention has reference to tunnel kilns or ovens and like structures, hereafter referred to generally as kilns. In a kiln of this type goods which may be articles or materials of various kinds are heated for various purposes while passing through a heating zone of the kilns, and are afterward cooled while passing through a cooling zone of the kilns which may be a portion of the same kiln chamber as that 20 including the heating zone or may be a separate chamber from the heating zone.

The object of the invention is to provide a kiln of the character referred to with simple and effective means whereby the heat 25 abstracted in the cooling zone from the goods treated and the trucks or other goods carriers may be utilized for generating steam available for power or other purposes. For this purpose I provide the cooling zone 30 of the kiln with suitably disposed pipes or conduits through which water is caused to circulate in such manner and with such speed that the water will be heated to the temperature of steam at a pressure suitable 35 for power and other purposes and provide in conjunction with these pipes, the other elements, ordinarily including a steam and water drum necessary to form a steam generating boiler of which the pipes in the 40 cooling zone of the kiln form the water heating section. The invention is of especial utility where the goods are of a kind permitting them to be rapidly cooled without injury after being heated to a high 45 temperature.

The various features of novelty which characterize my invention are pointed out with particularity in the claims annexed to and forming a part of this specification. 50 For a better understanding of the invention, however, and the advantages possessed by it reference should be had to the accompanying drawings and descriptive matter in which I have illustrated and described 55 a preferred embodiment of the invention.

Of the drawings:

Fig. 1 is a somewhat diagrammatic longitudinal sectional elevation;

Fig. 2 is an elevation in section taken similarly to Fig. 1, but on a larger scale 60 and showing a portion only of the apparatus shown in Fig. 1;

Fig. 3 is a transverse section taken on the line 3—3 of Fig. 1; and,

Fig. 4 is a sectional plan of the portion 65 of the apparatus shown in Fig. 2.

In the drawings I have illustrated the use of my invention in a kiln of the well-known Dressler type as shown for example by my prior Patents 1,023,628 and 1,170,428 but 70 having certain special constructive features arising from the use therein of the present invention and also arising from the fact that the particular kiln, shown by way of example, is intended for use in the fractional distillation of coal. The special features of kiln construction adapting the kiln for use in distilling coal form no part of my present invention but are disclosed in detail and claimed in my co-pending application, Serial No. 338,008 filed of even date herewith. This particular form of kiln is one in which the temperature conditions are such as to make the steam generating features of especial value, though they can 85 be utilized to advantage with kilns employed for many other purposes.

As shown, the kiln comprises a kiln chamber A enclosed by a refractory masonry wall B, the latter being usually insulated with 90 kieselguhr or the like. The kiln is formed with the usual benches C throughout the heating up and high temperature zone of the kiln, these benches being located at opposite sides of the pathway for the goods to be 95 treated which in case of the particular kiln illustrated is coal. On the benches C are mounted the combustion chambers H which may be formed of the usual hollow walled sections commonly employed in Dressler 100 kilns. The goods to be treated are carried through the kiln on trucks D or other carriers, the trucks entering the kiln at the inlet end past double doors E and leaving the kiln at the opposite end past double 105 doors F. This double door arrangement permits of the proper insertion and removal of trucks without any appreciable entrance of air to, or escape of gases from the kiln. Means which may be of any usual 110

or suitable type are provided for introducing fuel and air for its combustion into each combustion chamber. The means shown for this purpose comprise a gas supply nozzle HB and an air supply port HA' at one end of each combustion chamber. The two ports HA' receive air from an air supply conduit. The products of combustion leave each combustion chamber proper 10 at its end remote from that at which air and gas are supplied as aforesaid, and pass into heat radiating pipes I through which the products of combustion pass to an outlet conduit J. The pipes I are located on 15 the benches C and extend along the heating up zone of the kiln.

Advantageously in some cases means may be employed, as shown, to utilize the heat in the products of combustion leaving the 20 kiln through the conduit J to preheat the air supplied to the combustion chambers H by the conduit HA. As shown, the conduit J is connected by a conduit J', and the conduit HA by a conduit HA' to a 25 recuperator R and the latter is provided with an air inlet R', and a stack outlet R' for products of combustion.

For its special use in distilling coal, the kiln is provided with a gas space above the 30 pathway for the goods and goods carrier which is of considerable volumetric capacity, and is divided into a series of open ended compartments by partitions B' which extend across the kiln chamber at intervals above 35 the pathway for the goods. Each of these compartments is provided with a separate valved outlet B' through which a regulated escape of gas collecting in the compartment may be provided, all as is more fully 40 described in my co-pending application referred to above.

The goods and goods carrier cooling and steam generating apparatus which is the characteristic feature of the invention 45 claimed herein comprises, in the preferred construction illustrated, a series of water tubes K' at each side of the pathway for the goods, and another group of water tubes K² lying above the pathway for the goods. Advantageously as shown these tubes are 50 slightly inclined to the horizontal, rising from their ends remote from the ends of the combustion chambers. The tubes K' and K² are connected to a header K³ which is horse-shoe shaped with its legs or depending branches extending down at the sides of the pathway for the goods and connected to the tubes K', while the tubes K² are connected to the body or yoke portion of the header. 55 The opposite ends of the tubes K' and K² are connected to a similar header K⁴. Water is supplied to the header K⁴ by a supply pipe M shown as the delivery pipe of a boiler feed pump M which may be of usual 60 type. From the top of the drum or header

K³ leads a discharge pipe O which is connected to a horizontally disposed steam and water drum N shown as mounted above the kiln. As shown the pipe O is connected to the steam and water drum N by a connection O' opening into the drum below the water level therein and by another branch O² opening into the top of the steam and water drum. The steam and water drum N is provided with an outlet P for steam and 75 with a safety valve Q. To prevent the header K³ from absorbing heat too rapidly from, and thereby unduly cooling, the adjacent ends of the combustion chambers H, I

80 insert heavy masonry walls B³ between the ends of the combustion chambers and the corresponding portions of the header K³ and provide flat arches B⁴ over the pathway for the goods above these walls B³. These flat arches may be advantageously separated by 85 air pockets as shown in Fig. 2. The side walls B³ and the arch B⁴ are shaped to fit above the loaded goods carrying cars with only the necessary clearance. The constriction in the kiln chamber thus formed minimizes circulation of the kiln atmosphere by 90 which the cooling zone might tend to cool the high temperature zone of the kiln. The width of the kiln chamber will ordinarily, 95 as shown in the drawings, be substantially less in the cooling zone section of the kiln than in the heating up section.

In operation, the loaded goods carrying trucks D are periodically inserted into the kiln one at a time past the doors E and as each car is thus inserted the train of cars filling the kiln chamber is moved forward a carlength, a car being removed from the cooling zone of the kiln past the doors F each time a car is inserted in the kiln past 105 the doors E. As a car slowly moves from the doors E to the walls B³ it is slowly and gradually heated up to its maximum temperature, and as the car is passed through the cooling zone the sensible heat in the 110 goods and the car itself is to a large degree transferred to the water filled tubes K' and K² of the steam generating unit. The amount of heat thus abstracted and the temperature differentials are such as to permit 115 of the generation of a substantial amount of steam at pressures suitable for ordinary power purposes. The rapid rate at which the goods and cars are cooled by the steam generating unit makes it possible to cool the 120 goods and cars to a temperature at which they may be discharged from the kiln without injury and without an undesirable loss of sensible heat with a length of cooling zone substantially shorter than is necessary 125 with the cooling arrangements heretofore ordinarily employed in kilns of this character. The shortening in the length of the kiln structure thus made possible materially reduces the cost of kiln construction 130.

and reduces the ground space required for the kiln, which is a matter of much practical importance in some cases.

The particular construction and arrangement of the steam generating unit is one which is well adapted for efficient and successful operation in the manner disclosed. As the water moves through the tubes K' and K^2 from the header K^4 to the header K^3 , the water is gradually heated up to a temperature corresponding to the steam pressure desired. The provision of the steam and water drum well above the tubes and connected to the header K^3 as shown, reduces water hammer and other troubles which might result from the conversion of considerable quantities of water into steam in the tubes K' and K^2 and the header K^3 . The use of means such as a recuperator R for utilizing the sensible heat in the products of combustion to preheat the air required for combustion makes it possible to obtain the economy in fuel resulting from a proper pre-heating of the air supplied for combustion without drawing this air through the cooling-off zone of the kiln as has heretofore been the practice.

While in accordance with the provisions of the statutes I have illustrated and described the best form of embodiment in my invention now known to me, it will be apparent to those skilled in the art that changes may be made in the form of apparatus disclosed without departing from the spirit of my invention as set forth in the appended claims and that in some cases certain features of my invention may be used to advantage without a corresponding use of other features.

Having now described my invention, what I claim as new and desire to secured by Letters Patent, is:

1. In a tunnel kiln in which the kiln chamber comprises a heating zone and a cooling zone successively traversed by the goods passing through the kiln, the improvement which consists in a steam generating unit comprising water heating elements located in the kiln chamber in position to abstract heat from the goods as the latter pass through said cooling zone.

2. In a tunnel kiln comprising a heating zone and a cooling zone and a pathway through the kiln for goods, the improvement which consists in horizontally disposed water tubes located in the cooling zone portion of the kiln at the sides and above said pathway, and elements cooperating with said tubes to form a steam generating unit.

3. In a tunnel kiln comprising a heating zone and a cooling zone with a pathway through the kiln for goods, the improvement which consists in a steam generating unit comprising headers at each end of the cooling zone which extend over and having leg portions projecting down at the sides of the pathway, tubes connecting said headers, a steam and water drum external of the kiln to which the header at the hot end of the cooling zone is connected and means for forcing feed water into the header at the other end.

4. In a tunnel kiln comprising a heating zone and a cooling zone with a pathway through the kiln for goods, the improvement which consists in a steam generating unit comprising water heating elements located in said cooling zone in position to abstract heat from the goods passing through said zone, and a barrier at the junction between the heating and cooling zones closely encircling said pathway to minimize a circulation of kiln atmosphere between the heating and cooling zones.

5. In a tunnel kiln comprising a heating zone and a cooling zone with a pathway through the kiln for goods, the improvement which consists in a steam generating unit comprising water heating elements located in said cooling zone in position to abstract heat from the goods passing through said zone, and a barrier at the junction between the heating and cooling zones closely encircling said pathway to minimize a circulation of kiln atmosphere between the heating and cooling zones, the portion of said barrier above the pathway being formed of flat arches separated from one another by air spaces extending transversely to the pathway.

6. In a tunnel kiln comprising a heating zone and a cooling zone with a pathway through the kiln for goods, and combustion chambers located in the heating zone and fuel supply means and air inlets for the combustion chambers, the improvement which consists in a steam generating unit comprising water heating tubes located in the cooling zone and in combination therewith means for utilizing the hot products of combustion leaving the combustion chambers for preheating the air supplied to the air inlets of said combustion chambers.

Signed at New York, in the county of New York and State of New York, this thirteenth day of November A. D. 1919.

CONRAD DRESSLER.
